UNITED STATES PATENT OFFICE

PAUL E. PEARSON, OF SEATTLE, WASHINGTON, ASSIGNOR TO CONTINENTAL CAN COMPANY, INC., A CORPORATION OF NEW YORK

SALTER

Application filed May 1, 1930. Serial No. 449,035.

This invention relates to salters, and it has reference in particular to machines designed for use in a canning line for dispensing measured amounts of salt into the cans as they 5 are advanced in succession to the filling machines.

Heretofore, machines for the above purpose have been used in operative connection with can conveyers, as is the machine in the 10 present instance, and the salt dispensing valves of the machines have been timed to operate at regular intervals in accordance with the movement of the conveyer. While such machines to a certain extent have been 15 satisfactory, there has been the undesirable results of spilling and wasting salt in the event that the cans became out of time, or when the delivery of cans by the conveyer became irregular or exhausted, since no satisfactory provision has heretofore been made 20 to positively time, or stop the cans to receive the salt, or has any means been provided to cause the discharging of salt to be discontinued in the event no can is present on the 25 conveyer to receive it. In other words, the salter, as heretofore used, was operated to deliver certain amounts of salt at regular intervals and this result took place so long as the machine was in operation and regardless 30 of whether or not cans were in position to receive the salt.

In view of the above undesirable results of machines as heretofore used, it has been the principal object of the present invention 35 to provide an improved mechanism whereby the movement of the cans to the machine is accurately timed in accordance with the actuation of the salt dispensing valve so that no salt is wasted by reason of the can passing 40 the valve too soon or too slow, since it is manifest that unless the cans are accurately timed in accordance with the action of the dispensing device much salt can be wasted. It is also an object to provide for temporarily 45 stopping each can beneath the discharge valve

while the valve is dispensing a charge of salt, thereby insuring that the entire charge will be deposited within the can, and not over the edges thereof.

Another object of the invention has been 50 to provide means whereby the dispensing valve is temporarily rendered inoperative in the event that no can is present on the conveyer to receive the charge of salt, but which immediately causes the valve to resume operation as soon as the can supply is resumed. 55

More specifically stated, the present invention resides in the provision of a salter in which a worm shaft is employed to time the delivery of the cans to the salt receiving position and to then hold them there during the salt dispensing operation of the valve. Also to provide for driving the valve through a clutch connection, and to provide a release lever normally held in inoperative position 60 by cans in the line, but which operates incident to the absence of a can in the line to release the clutch so that no salt will be delivered at that time. 65

Another object of the invention is to provide 70 a salt dispensing valve of novel construction.

Other objects of the invention reside in the various details of construction, and in the combination of parts, and in their mode of 75 operation, as will hereinafter be described.

In accomplishing these and other objects of the invention, I have provided the improved details of construction, the preferred forms of which are illustrated in the accompanying drawings, wherein:— 80

Fig. 1 is a front elevation of a salter embodying the present invention.

Fig. 2 is a top or plan view of the same.

Fig. 3 is a sectional detail through the 85 salt hopper illustrating the construction of the dispensing valve.

Fig. 4 is a vertical section transversely of the machine, through the salt hopper and dispensing valve. 90

Fig. 5 is a sectional detail of the clutch mechanism which provides the driving connection for the salt dispensing valve; this view taken on line 5—5 in Fig. 2.

5 Fig. 6 is a section taken on line 6—6 in Fig. 5.

Fig. 7 is an enlarged plan view of the timing worm which times the delivery of cans to the salter.

10 Referring more in detail to the drawings,—

In a preferred form of construction, the present machine comprises a horizontally disposed base or frame structure which is supported at suitable height by end frames, 15 or legs 2—2; these being bolted to the frame and are braced by a connecting cross bar, or rod 3. Mounted at one end of the frame 1 is a transverse shaft 4 revolvably supported in bearings 5—5, and equipped at its outer end 20 with a belt wheel 6 through which it may be driven. A sliding clutch 7 is keyed on the shaft 4 and is adjustable, by means of a hand lever 8, into and from locked relation with clutch jaws 6' formed on the hub of 25 the belt wheel to throw the machine into or out of gear. The hand lever 8 is pivotally supported at its lower end by means of a bolt 9 mounted in a bracket 9' that is fixed to the main frame, and connection between the lever 30 and the clutch collar 7 is provided by a pin 8' fixed in the lever and extended into the encircling groove 7' of the collar.

At the end of the frame 1, opposite that which carries the shaft 4, is a transverse 35 shaft 10 revolvably mounted in suitable bearings, as at 10', and a pair of conveyer chain belts 11—11, in spaced relation, operate about the sprocket wheels 12 and 13 that are fixed on the shaft 4 and 10 respectively. The top 40 runs of the two conveyer belts are contained in guide grooves 15 in the top wall of the frame 1, and they serve as means on which the cans 16 are moved through the machine and past the salter. Sprocket wheels 17 and 45 18 are fixed on the shafts 4 and 10 respectively and they carry conveyer chain belts 19 and 20, see Figure 2, whereby the cans may be brought to and taken away from the machine. The two parallel conveyer belts 11—11 are 50 advanced incident to rotation of the shaft 4 and they drive the shaft 10, which through mechanism presently described, drives the salt dispensing valve mechanism.

Mounted on the frame 1 along one side of 55 and parallel with the conveyer chains, is a timing worm shaft 24. This is revolvably mounted at its ends in bearings 25 and 26. One end of the worm shaft is equipped with a beveled, driving gear 27 which meshes with 60 and is driven by a beveled gear 28; the latter gear being mounted on a driven shaft 29 that is disposed directly above the shaft 10, and is supported by a bearing 30; the bearing 30 being supported by a bracket 31 that 65 is fixed to the frame 1. Spur gears 32 and

33 are fixed in mesh on the shafts 24 and 10 respectively, so that the worm shaft is rotated in accordance with the advance movement of the conveyer belts 11—11.

The cans 16, which are delivered by belt 70 20 onto the conveyer belts 11—11, are urged against the spiral thread of the worm shaft by an outwardly yieldable pressure shoe 34. This shoe is pivotally mounted by a bolt 35, and it is urged against the cans by pressure thereagainst of a counterweight 36. The worm in the present instance advances slower than the conveyer belts and therefore it acts to retard the advance movement of the cans. In this way, the worm serves to positively time the delivery of the cans to the salt receiving position.

75 The salter mechanism consists of a container 40 that is supported by a bracket 41 adjustably fixed to the base frame 1 so that the salter mechanism may be raised or lowered to suit the height of the cans that are being passed through the machine. The salt container is of hopper-like form and at the base 80 is provided with a discharge opening 42 beneath which is a delivery spout 43 through which salt is delivered to the cans as they pass successively beneath the device.

85 The means for measuring and dispensing the salt consist of a disc valve 45 that is rotatably fitted within a circular portion at the base of the hopper. This disk is provided with a drive shaft 46 that extends outwardly 90 from the housing through a bearing 47, and at its outer end is equipped with a gear 48 which is driven by a spur gear 49 carried on a shaft 50, and which, in turn, is revolvably mounted in a bearing 51 formed integral with the side plate of the hopper. A sprocket 52 95 is fixed on the outer end of shaft 50 in alignment with a similar sprocket 53 on the end of the shaft 10, and a drive belt 54 extends about these sprockets to provide a driving connection between the salter and shaft 10. Formed diametrically of the discharge valve, 100 is a channel 56 in which a slide 57 is fitted. The slide is of a somewhat shorter length than the diameter of the valve, as is shown in Fig. 3, and it has two studs 58 and 59 extended therefrom into a cam opening 60 in a circular plate 61 that is fixed, as shown best in 105 Figure 1, to the face of the hopper.

110 The function of the cam plate and the studs is to produce a back and forth sliding action 115 of the slide as the disc valve revolves so that certain measured amounts of salt will be taken into the upper end of the channel when the parts are in position as in Fig. 3, then when this end of the channel has been rotated to a position over the discharge spout, the slide will be actuated downwardly to discharge the salt and by this movement to open the upper end of the channel to receive the charge for the next can.

120 There is also provided an agitator and 125

5 packer 65 on the inner end of the shaft 50. This consists of a plurality of radially directed fingers which rotate with the shaft to keep the salt stirred up and in loose condition.

10 One of the principal features of the present machine resides in the details of construction of the timing worm whereby the cans are held in position directly below the dispensing valve spout 43 during the period of time that the valve is discharging. This is accomplished by extending the thread of the worm directly about the worm shaft at the proper place, as indicated at 65' in Figures 1, 2 and 6. It will be noted that the thread 65 leads spirally along the worm shaft up to this position and is then extended directly about the shaft for approximately one hundred eighty degrees and then tapers 15 off in a spiral direction. This portion 65' of the thread is in a plane at right angle to the shaft and positively stops the advance movement of the cans directly beneath the discharge valve and retains them stationary 20 during the period that the salt is being dispensed. By this provision, much salt is saved as ordinarily the movement of the can is not interrupted and the salt is discharged while the can is passing, and incidentally, much 25 salt is spilled onto the can edges and to the outside of the can.

30 Another feature of the present invention resides in the means for preventing delivery of salt in the event no can is on the conveyer 35 to receive it. It is to be observed that the salt dispensing valve is operated through a driving connection with the shaft 10. This construction comprises the sprocket belt 54 and the sprocket wheel 53 that is driven by 40 the shaft 10. The sprocket wheel 53, in this instance, is revolvably mounted on the shaft but is driven through the medium of a locking pawl 70 that is pivotally mounted by a pin 71 on a drum 72 that is fixed on the shaft 45 10, as shown best in Figures 5 and 6. A small spring 73 is attached to the drum and to the pawl and this normally holds the inner end of the pawl in driving contact with a shoulder 75 formed on the hub portion of 50 the sprocket wheel. The opposite end of the pawl extends outwardly from the drum, as in Fig. 5. So long as this connection is provided, the shaft 10 operates to drive the sprocket 53 and this, through the belt and 55 gears previously described, rotates the salt dispensing valve. Pivotally mounted on a stud 80 supported by a bracket 81 from the side of the frame 1, as shown in Figures 1 and 7, is a lever 85 having an elongated end 60 portion extended into the path of travel of cans delivered to the salter, and having a short opposite end disposed directly above the drum which carries the pawl 70 but normally out of the path of rotative movement 65 of the pawl. A spring 86 is attached to the

lever to draw the longer end portion thereof inwardly into the path of movement of the cans 16. The presence of cans on the conveyer operates to retain the lever at such position that its shorter end portion does not come in contact with the outer, extended end of the locking pawl 70, but in the event that a can is absent from the conveyer, the spring 86 pulls the lever inwardly thereby causing its shorter end portion to swing outwardly, as shown at 85' in dotted lines in Figure 2, so that it directly overlies the path of the pawl and when the outer end of the pawl engages therewith, its inner end is thereby released from driving connection 80 with the hub of the sprocket wheel 53, and the driving connection with the salter is thereby temporarily disconnected, and no salt is dispensed. As soon as the can supply on the conveyer again is resumed, the lever 85 is actuated outwardly and this releases the shorter end from the pawl and causes the pawl to again engage the shoulder 75 and operation of the salt dispensing valve to be resumed. 90

It is to be understood that the various gears and sprockets employed in the driving connections are so arranged that the movement of the cans is positively timed in accordance with the rotative movement of the dispensing 95 valve and the salt is dispensed exactly at the proper time to prevent any possible waste.

Having thus described my invention, what I claim as new therein and desire to secure by Letters Patent, is:

1. A machine of the character described, comprising a material containing hopper, a continuously moving conveyer by which cans are delivered in succession beneath the hopper to receive material therefrom, a worm shaft adjacent the conveyer and operable to space the cans and to time their delivery to and from receiving position, a dispensing valve in the hopper operable in synchronism with the worm shaft to deliver measured amounts of material to each can while in receiving position, a driving means for the valve mechanism including a releasable connection, and means operable incident to the absence of cans in regular order of delivery 110 to the hopper to actuate the releasable connection to temporarily discontinue actuation of the valve mechanism. 115

2. A machine of the character described, comprising a material containing hopper, a 120 conveyer belt on which cans are delivered in succession beneath the hopper to receive material therefrom, a worm shaft associated with the conveyer whereby the cans are timed in their delivery to and from receiving position, a dispensing valve in the hopper operable to deliver measured amounts of material therefrom to the cans while in receiving positions, means for rotating the worm shaft, means synchronized therewith for actuating 125 130

the valve in synchronism with the worm shaft including a continuously revolving shaft, a revolute element operatively connected with the valve and having a clutch shoulder, and 5 a releasable clutch pawl mounted on the shaft and normally engageable with the shoulder to effect a driving connection with the revolute element for actuating the valve, a pivoted lever extended into the path of delivery 10 of cans to the machine and normally held in inactive position by the cans, and a spring for moving the said lever incident to the absence of a can in regular order into position to engage with and release the clutch pawl to 15 preclude actuation of the dispensing valve.

3. In a machine of the character described, a hopper provided with a discharge opening, a dispensing valve for controlling the delivery of material through the opening; said 20 valve comprising a disc revolute in the opening and provided at one side with a transverse channel, the opposite ends of which are successively presented to the interior of the hopper and to the discharge opening as the 25 disc revolves, a slide fitted in the channel and which is of shorter length than the channel, a cam plate fixed to the hopper to overlie the slide and having an opening provided with a cam surface, means on the slide engaging 30 the cam surface to effect reciprocal action of the slide as the disc revolves to permit the intaking of material from the hopper into the channel ends as they move through the hopper and to effect the ejection of the mate- 35 rial as the channel ends pass the discharge opening.

4. A salt dispensing machine, comprising a hopper having a discharge opening, a conveyer for delivering cans in succession to the 40 hopper, a worm shaft operable to time the delivery of cans to and from the hopper and valve mechanism synchronized with the timing means for controlling the delivery of salt from the hopper to the cans, said dispensing 45 valve comprising a revolute disc within the opening provided with a transverse channel, a slide fitted in the channel, a cam mounted on the hopper, a cam follower on the slide whereby the latter is caused to reciprocate 50 incident to rotation of the disc to permit the intaking of measured amounts of salt into the channel ends as they revolve through the hopper and to effect the discharge of these measured amounts to the cans.

5. In combination, a hopper having a dispensing valve, a continuously moving conveyer belt operating beneath the valve and on which cans may be placed promiscuously for delivery beneath the dispensing valve to 60 receive material from the hopper, a continuously rotating timing screw operable to space and time the cans as delivered on the belt to the dispensing valve and for temporarily checking the advance movement of each can, 65 without removing it from the belt, when in

position to receive material from the valve, means for actuating the valve in synchronism with the timing screw to dispense material from the hopper into each can positioned beneath the valve and means operable 70 incident to absence of a can in its regular order of delivery by the screw to temporarily prevent actuation of the dispensing valve.

Signed at Seattle, Washington this 25th day of April 1930. 75
